WINDOW LOCK

Richard Monroe, Houston, Tex.

Application July 20, 1949, Serial No. 346,465

3 Claims. (Cl. 292—228)

This invention relates to a window lock.

An object of the invention is to provide a lock of the character described whereby a lower window sash may be locked, at any desired elevation, against upward movement relative to the upper sash.

It is another object of the invention to provide a window lock which will automatically lock upon downward movement of the lower sash and which may be readily released from the inside of the room only, when it is desired to elevate the lower sash.

It is a further object of the invention to provide a window lock having a guard which will prevent access to the lock from without and thus prevent the unauthorized release of the lock and elevation of the window sash.

With the above and other objects in view the invention has particular relation to certain novel features of construction, operation and arrangement of parts, an example of which is given in this specification and illustrated in the accompanying drawing, wherein:

Figure 1 shows a fragmentary, front elevational view of the sashes of a window shown 25 locked in closed position.

Figure 2 shows an enlarged, fragmentary, sectional view taken on the line 2—2 of Figure 1, and

Figure 3 shows an enlarged, fragmentary, cross-sectional view taken on the line 3—3 of Figure 2.

Referring now more particularly to the drawing wherein like numerals of reference designate the same parts in each of the figures, the numeral 1 designates a housing preferably formed of sheet metal and which may be of any selected contour. The housing is provided with a lateral flange 2 provided with openings to receive the screws 3, 3 whereby the housing may be secured to the top of the lower window sash 4 as shown in Figures 1 and 3. The housing is enclosed on all sides excepting the side facing the upper sash 5 which latter side is open.

The open side of the housing is fitted closely against the vertical metal strip 6 which is secured at its upper and lower ends by the screws 6a, 6a, to the inside of the frame of the sash 5 and which is preferably slightly countersunk into said frame as shown in Figure 3. The side margins of the strip 6 are overturned inwardly, or toward each other, forming the flanges 1, 1. The strip 6 is formed with downwardly and inwardly pitched ratchet teeth 8, as more clearly shown in Figure 2.

The bottom of the housing is closed by the top of the sash 4 and within it and fastened to the top of said sash by the screws 9 there is a plate 10 whose side margins are upwardly turned and formed with the ears 11. Fastened to these ears there is a transverse rod 12.

Within the housing there is a plate-like dog 13 having the downwardly turned marginal flanges 14 formed, at their inner ends with the bearings 15 on said rod whereby the dog is pivotally mounted. This dog is extended inwardly forming a pressure plate 16. Surrounding the rod 12 there is a coil spring 17 one end of which is retracted and clamped underneath the inner end of the plate 10 and which is thereby anchored in place. The other end of the spring is extended through an opening in the pressure plate 16 and the spring normally acts against the dog 13 to hold its free end in position to engage with the ratchet teeth 8 so as to lock the lower sash 4 against upward movement. The inner side of the housing 1 is formed with an inwardly swinging door or shutter 1a which may be opened for access to the pressure plate 16. The pressure upon said plate will release the dog 13 from the ratchet teeth and permit the elevation of the lower sash 4 which may be raised by means of the usual lift 4a.

It will thus be obvious that when it is desired to open, or elevate, the lower sash the dog 13 may be released and the sash elevated to the desired level and upon release of the pressure plate 16 said dog will automatically engage the corresponding ratchet tooth 8 to prevent further elevation of the lower sash. As the lower sash is lowered the free end of the dog 13 will ride over the teeth 8 and said sash may be lowered until it is closed and will be automatically locked in closed position.

Within the housing 1 there is a guard 18 of a general rectangular shape but whose side walls are slightly flared inwardly. At its outer side said side walls are outwardly turned forming the vertical flanges 19, 19 which engage behind the flanges 1, as also shown in Figure 3, thus providing a sliding connection between the guard 18 and the strip 6. The upper and lower ends of the guard 18 fit closely against the strip 6 between its side flanges 1, as shown in Figure 2. This guard is provided to prevent access to the dog 13 from without so that the dog cannot be released, and the lower sash unlocked, by the insertion of an instrument from the outside upwardly between the two sashes.

The drawing and description are illustrative merely, the invention being limited only by the appended claims.

What I claim is:

1. A window lock comprising a housing adapted to be secured to a movable window sash, a dog pivotally mounted within the housing, yieldable means normally holding the free end of the dog projected from the housing into position to engage with a fixed ratchet to lock the sash against movement in one direction, said dog being mounted to allow movement of the sash in the other direction, an approximately rectangular guard in the housing and having a sliding connection with the ratchet and through which the dog works, said guard being arranged to prevent access to the engaging end of the dog.

2. A device of the character described comprising a strip formed with ratchet teeth and whose side margins are overturned inwardly forming flanges, a housing adjacent said strip and whose side facing the strip has an opening, a guard within the housing around the opening and having side walls whose margins adjacent said strip are outwardly turned forming flanges which engage the flanges of said strip to form a sliding connection between the guard and strip and means mounted within the housing arranged to work through the guard and opening and to engage the ratchet to lock the housing against movement in one direction and being

mounted to release the ratchet to allow movement of the housing in the other direction, said guard being provided to prevent access to said engaging means.

- 5 3. A device for locking window sashes comprising an elongated ratchet member formed with ratchet teeth and having inwardly turned marginal flanges, said ratchet members being adapted to be secured to a window sash, a housing adapted to be secured to another sash and arranged adjacent said ratchet member, the side of the housing adjacent said member being provided with an opening, a guard within, and movable with, the housing, and arranged around the 10 opening and having side walls whose margins adjacent said ratchet member are outwardly turned forming flanges which engage the flanges of said member to form a sliding connection between the guard and ratchet member, yieldable means mounted within the housing and having an operative end arranged to work through the guard and opening and to engage the ratchet to lock the housing against movement in one direction and being mounted to release the ratchet to allow movement of the housing in the other direction, the other end of said 15 engaging means being extended forming a pressure plate, said guard being provided to prevent access to said operative end of said engaging 20 means.
